UNITED STATES PATENT OFFICE.

JOHN ARTHUR JONES, OF DALLAS, TEXAS.

GARBAGE-CAN.

1,300,976.

Specification of Letters Patent. Patented Apr. 15, 1919.

Application filed November 15, 1918. Serial No. 262,676.

To all whom it may concern:

Be it known that I, JOHN A. JONES, a citizen of the United States, and a resident of Dallas, in the county of Dallas and State of Texas, have invented certain new and useful Improvements in Garbage-Cans, of which the following is a specification.

This invention relates to improvements in garbage cans and the like, and the object of 10 the invention is to provide a device of the character specified adapted for use on side walks and in public parks, wherein foot operable mechanism is provided for opening the lid of the can, which is normally spring 15 held closed, and wherein means is provided for limiting the opening movement of the door.

In the drawings:

Figure 1 is a vertical section of the im- 20 proved can, with parts broken away;

Figs. 2 and 4 are sections on the lines 2—2 and 4—4, respectively, of Fig. 1, each view looking in the direction of the arrows adja- 25 cent to the line;

Fig. 3 is a view similar to Fig. 1 showing the parts in another position;

Fig. 5 is a partial perspective view of the top of the receptacle;

Fig. 6 is a partial perspective view of the 30 door.

In the present embodiment of the invention an outer inclosing casing 1 is provided, the said casing having depending legs 2 for supporting the same and being substantially 35 rectangular in cross section and having a rounded top 3, as shown. The rear wall of the casing 1 is cut away to receive the tray or drawer 4 which seats within the casing 1, resting upon the bottom of the said casing 40 and being supported by a depending rib 5 on the drawer and by angle plates 6 on the bottom of the casing 1. At the cut away portion in the rear wall of the casing 1 there is an upstanding rib 7 within which the tray or 45 drawer 4 seats and the said tray or drawer is supported with its bottom spaced apart from the bottom of the casing 1 by the rib 5 and the angle plates 6. This tray or drawer has handles 8, by means of which it may be in- 50 serted and withdrawn from the casing 1, and the rear or outer wall of the drawer has an extension 9 which fits upon the commencement of the curved top 3 of the casing 1 as shown in Figs. 1 and 3.

55 This extension 9 has a slot through which passes a staple 10 on the curved top and a

pad-lock of usual construction may be engaged with the staple to lock the tray in place in the casing. The casing has an opening 12 in the front of the curved top, and this opening is provided with a door 13, the said door being curved transversely to fit the curved top. At the center of the curved top there is a slot or passage extending transversely of the said top, and a hood or housing 14 is secured to the top over this slot or opening. The said hood is substantially U-shaped in cross section and the rear edge of the door 13 extends through a slot or passage 15 in the front wall of the hood into the hood, as 70 shown. At its rear edge the door has eyes 16 which are engaged by flexible members 17, as, for instance, cords or wires, and the lower ends of these flexible members are connected to the arms 18 of a yoke shaped lever, 75 comprising the said arms and a body 19. The arms of the lever are pivoted to the rear legs of the casing 1, as indicated at 20, and coil springs 21 are interposed in the length of the flexible member.

80 The yoke 18—19 is beneath the bottom of the casing 1, and the flexible members 17 extend downwardly between the side walls of the tray and those of the casing. It will be evident that when downward pressure is 85 made upon the body 19 of the yoke, the rear end of the door will be drawn downwardly, swinging through the passage in the curved top 3 of the casing 1, as shown in Fig. 3, and the door will be swung away from over the 90 opening 12, to permit the insertion of material in the tray.

A plate 22 is secured to the rear edge of the door, by means of the eyes 16, the said rear edge being reduced or cut away at each 95 end, as shown at 23 in Fig. 5, to enter the slot or passage 15, and the shoulders formed at the inner ends of the cut away portion act as limiting members for limiting the movement of the door into the hood. The forward edge of this plate 22 is bent upwardly, as indicated at 24, to form a flange or rib for engaging the front wall of the hood, to limit the outward movement of the door, as shown in Fig. 1. The door is thus balanced on the 100 forward edge of the opening which the hood 14 covers, and it may be swung into the open position of Fig. 3 or permitted to fall into the closed position of Fig. 1.

105 In use, the parts are arranged as shown in Fig. 1. When it is desired to insert material in the tray, the foot is placed upon the

body 19 of the yoke and downward pressure is made. This swings the rear end of the door downwardly, lifting the door from over the opening 12 and permitting the insertion of the said material. As soon as the yoke is released the weight of the door returns the parts to normal closed position. The engagement of the edges of the shoulders 23 with the ends of the passage 15 limits the inward movement of the door with respect to the casing, and the flange or rib 24 limits the outward movement.

I claim:

1. A receptacle comprising a casing having supporting legs and a top curved from front to rear of the casing, the rear wall of the casing being cut away from the curved top to near the bottom, a tray seated within the casing, said tray having at its rear edge a depending rib resting upon the bottom of the casing and the casing having an upstanding flange engaging outside of the rib and having means for supporting the front end of the tray spaced above the bottom of the casing, said casing having an opening in the curved top extending transversely of the casing, a housing arranged above the opening and having a passage in its front wall, said casing having an inlet opening at the front of the curved top, a door fitting the

curved top for closing the inlet opening and having a reduced portion extending through the passage into the housing, shoulders being formed between the reduced portion and the body of the door for engaging the ends of the passage to limit the inward movement of the door, said door having a rib for engaging the front wall of the housing to limit the outward movement of the door, and foot operated means for opening the door, the door closing by gravity.

2. A receptacle comprising a casing having its rear wall cut away, a tray seated within the casing and having at its rear edge a depending rib resting upon the bottom of the casing and the casing having an upstanding flange engaging outside of the rib, and having means for supporting the front end of the tray spaced above the bottom of the casing, the rear wall of the tray having a hasp and the casing having a staple for engagement by the hasp to prevent upward movement of the rear end of the tray to disengage the same from the upstanding flange and the staple being adapted to receive a lock to lock the tray in the receptacle.

JOHN ARTHUR JONES.
